UNITED STATES PATENT OFFICE

2,610,385

METHOD OF MAKING GEM SETTINGS

Moe Manne, New York, N. Y., assignor to Manne Enterprises, Ltd., New York, N. Y., a corporation of New York

Application August 5, 1949, Serial No. 108,800

4 Claims. (Cl. 29—10)

1

This invention relates to jewelry settings, and particularly to a method of manufacturing the same.

At the present time, in the mounting or setting of jewels, and particularly diamonds, it is customary to surround the set gem by reflecting surfaces, and especially angularly-disposed, highly polished surfaces, for the purpose of enhancing the brilliancy of the stone and serving to create the effect of a stone of greater size than that actually used. In mounting or setting a stone in this manner, the usual procedure is to mount the stone in the aperture provided in the setting for its reception, by the utilization of parts of the metal around the stone to form prongs to overlie the edge of the stone to hold it in place. When this is done, excess metal then disposed around the stone is removed to an extent required to form the angular reflecting surfaces; these surfaces are then polished until smooth and shiny, and the setting is then complete. The operations above stated are time-consuming and must be performed by experienced and highly-skilled and well-paid workmen, thus materially increasing the production cost of the jewelry of which such a setting forms a part, hence it is done only in higher-priced jewelry.

With the difficulties of producing settings of the above character in mind, the present invention contemplates the provision of a method of making setting wherein the procedure involved is greatly simplified; the cost of production is very materially reduced and the work involved may be performed by workmen of relatively little skill, and hence the price of the finished jewelry reduced very substantially.

More particularly, the invention contemplates the provision of a method of making a setting wherein the reflecting surfaces which extend along the sides of the set jewel are produced by stamping or by dies, and are completed and highly polished before an attempt is made to set the jewel. Material for use in formation of the jewel-retaining prongs or pins is provided between and independent of the polished reflecting surfaces; the setting is pierced to provide the apertures for the stones, which are then placed in the apertures so provided, and the material for the prongs or pins is distorted or spread to engage over the jewels and hold the same in place, the operations as above set forth in no manner changing, marring or disturbing the polished reflecting surfaces as initially provided on the setting.

With these and other objects to be hereinafter set forth in view, I have devised the method and

arrangement of parts to be herein disclosed and more particularly pointed out in the claims appended hereto.

In the accompanying drawing, wherein an illustrative embodiment of the invention is disclosed, Fig. 1 is a top plan view of a setting made in accordance with the present invention and prior to the mounting of the gem; Fig. 2 is a top plan view of the setting with the gems mounted therein; Fig. 3 is a longitudinal sectional view through the setting with the gems mounted as shown in Fig. 2; Fig. 4 is a sectional view taken on the line 4—4 of Fig. 1, looking in the direction of the arrows; Fig. 5 is a top plan view of a differently shaped setting made in accordance with the invention; Fig. 6 is a top plan view of a double-row setting before the gems are mounted therein; Fig. 7 is a side view of the same, and Fig. 8 is a sectional view taken on the line 8—8 of Fig. 6, looking in the direction of the arrows.

Referring to the embodiment of the invention shown in Figs. 1 to 4 inclusive, the setting consists of an elongated bar or strip 1, preferably but not necessarily of precious metal. The setting may be flat, or in the case of a finger ring setting it may be curved or arcuate as shown in Fig. 7. The setting, as disclosed in Figs. 1 to 4, is channel shaped. That is to say, its concave top or upper face is provided with the two inclined reflecting surfaces 2 and 3 which, in the finished setting, diverge from the set stones and are highly polished to enhance the appearance of the gems and to create the effect of larger stones. Located between these angular polished reflecting surfaces 2 and 3, is a rib or bead 4, which is interrupted at suitably spaced, and preferably uniformly spaced, intervals by the gem-receiving areas shown as apertures 5 in which the gems 6 are mounted in the manner shown in Figure 2.

In the improved method of manufacturing the setting, the same is preferably stamped or died out to the shape shown in Figs. 1 and 2. The production of the setting by dies includes also the simultaneous formation of the inclined reflecting surfaces 2 and 3, which, after the setting is removed from the dies, and the holes 5 placed therein according to the size of the stones to be mounted, are polished and finished to the final high gloss. The polishing of the reflecting surfaces 2 and 3 thus takes place wholly before the stones are set and these finished and polished surfaces remain undisturbed by the gem-setting operation.

In setting the stones or gems 6, each gem is placed over the aperture 5 and portions of the

raised pin-forming rib or bead 4 located between the apertures 5 are shaped or distorted to form pins or lugs 7 which overlie the gems and serve as mounting prongs to hold the stones mounted in position over the several apertures 5. The utilization of the material of the rib or bead 4 for the formation of the gem-mounting prongs or pins, thus employs material located between the reflecting surfaces 2 and 3 and not constituting a part of such surfaces. Hence the mounting of the gems in this manner is performed in a way which does not disturb the polished surfaces 2 and 3 so that polishing of these surfaces subsequently to the gem-setting operation is unnecessary.

I have found that by finishing and polishing the reflecting surfaces 2 and 3 prior to the setting of the gems, and the mounting or setting of the gems by the employment of material remote from and forming no part of the reflecting surfaces, the polishing and completion of the surfaces is readily and economically done since, with the gems not in the setting, extraordinary care in polishing the surfaces 2 and 3 does not necessarily have to be exercised, yet a high and flawless polish is easily imparted to the surfaces 2 and 3. The rib 4, provided between the apertures 5, provides ample material for formation into gem-retaining prongs or lugs 7, and this rib, being elevated above and situated between the surfaces 2 and 3 is easily formed into the overlying prongs 7 which securely mount the gems.

In Fig. 5, a modification is disclosed, showing how the method of manufacture above described is employed in conjunction with settings of ornamental formation. Therein is shown a petal or leaf-shaped setting 10 having the two highly-polished, inclined reflecting surfaces 11 and 12 corresponding in function to those shown at 2 and 3, and between which a stone is adapted to be mounted. An aperture 13 is provided for the reception of the stone in the known manner, and a plurality of pin-forming ribs 14, extend radially from the aperture 13. That is to say, pins or prongs such as shown at 7 in Fig. 2, are formed from the material of these ribs to hold the gem seated. In producing a setting as shown in Fig. 5, the same is died out; the aperture 13 is drilled and the reflecting surfaces 11 and 12 are then polished to high gloss. The gem is then set by distorting material of the pin-forming ribs 14, to extend it over the stone and retain the stone in seated position over the aperture 13. It will again be noted in this embodiment of the invention, that the surfaces 11 and 12 are finished and polished prior to the gem-setting operation.

In Figs. 6 to 8 inclusive, a double-row setting, such as might be used in a ring, is shown. This is similar in construction to Fig. 1, except that it is adapted for the setting of two rows of stones. This setting is also made in the manner described, with the reflecting surfaces polished before the setting of the stones and the stones retained in place by distortion of the ribs 4 between the stones.

Several embodiments of the invention are shown in the drawing to illustrate the fact that the settings may be made in various ornamental forms, all of the same embodying, however, the same principle of manufacture and operation,

wherein the reflecting surfaces are pre-formed prior to the setting operation, and no material is required to be removed or polished after the setting operation in order to either provide or complete these reflecting surfaces. Hence the surfaces are smoother, flawless as to finish and polish and moreover can be produced economically and accurately by the method described.

Therefore, while I have herein described several embodiments of the invention, it is obvious that the same is not to be restricted thereto, but is broad enough to cover all structures coming within the scope of the annexed claims.

What I claim is:

1. The method of making a gem setting comprising forming a channel-shaped strip having a top face by dieing operations, said strip having its top face provided with inclined reflecting surfaces and a rib extending longitudinally between said surfaces, perforating the rib to provide gem-receiving apertures, polishing the inclined reflecting surfaces, and then setting gems over the apertures by retaining said gems in place by utilizing portions of the rib only as gem-retaining lugs.

2. A method of setting gems comprising the steps of, integrally fabricating a gem setting of a metallic material formed with a gem-receiving area and pin-forming members adjacent thereto, pre-polishing said gem setting contiguous to said gem-receiving area, and distorting only said pin-forming members adjacent said gem-receiving area to provide gem-retaining pins rigidly setting said gem.

3. A method of setting gems comprising the steps of, fabricating a gem setting of a metallic material formed with a gem-receiving area and pin-forming members adjacent thereto, pre-polishing said gem setting contiguous to said gem-receiving area and intermediate said pin-forming members to provide reflecting surfaces, thereafter placing a gem over said gem-receiving area, and distorting only said pin-forming members toward said gem-receiving area to provide gem-retaining pins rigidly setting said gem.

4. A method of setting gems comprising the steps of, fabricating a gem setting of a metallic material provided with a gem-receiving area and formed with adjacent reflecting surfaces and pin-forming members, pre-polishing said reflecting surfaces of said gem setting, placing a gem over said gem-receiving area, and distorting only said pin-forming members to provide gem-retaining pins rigidly setting said gem.
